(57) **CLAIM**

The ornamental design for a note tab package set, as shown and described.

DESCRIPTION

FIG. 1 is a perspective view of a note tab package set showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1-2 and 4-7 represent unclaimed subject matter and form no part of the claimed design.

The broken lines shown on the backing card of the note tab package set in FIGS. 1-3 represent perforation and form part of the claimed design.
